Assistant Examiner — Michael Chong

(74) Attorney, Agent, or Firm — Banner & Witcoff, Ltd.

(57) **CLAIM**

The ornamental design for a connector shell assembly, as shown and described.

DESCRIPTION

FIG. 1 is a front top perspective view of a connector shell assembly showing our new design;

FIG. 2 is a rear bottom perspective view thereof;

FIG. 3 is a top view thereof;

FIG. 4 is a bottom view thereof;

FIG. 5 is a right side view thereof;

FIG. 6 is a left side view thereof;

FIG. 7 is a front view thereof; and,

FIG. 8 is a rear view thereof.

The broken lines depicting the remainder of the connector shell assembly show features that form no part of the claimed design.
